UNITED STATES PATENT OFFICE.

GEORGE W. HILL, OF COMMERCE, OKLAHOMA.

PUMP-OPERATING MECHANISM.

Application filed October 4, 1921. Serial No. 505,310.

To all whom it may concern:

Be it known that I, GEORGE W. HILL, a citizen of the United States, residing at Commerce, in the county of Ottawa and 5 State of Oklahoma, have invented certain new and useful Improvements in Pump-Operating Mechanism, of which the following is a specification.

This invention relates to pump jacks, and 10 it comprises a frame adapted to be mounted on the casing of a pump and surround the plunger rod, a spring secured to said frame and said plunger rod, an operating lever pivotally mounted on said frame and connected to said plunger rod, means for connecting said lever to a power operated drive member, and means for connecting a handle to said lever.

An object of the invention is the provision 20 of means of cushioning the plunger rod on its downward stroke.

A further object is the provision of a pump construction which will permit smoother operation and reduce vibration.

25 A further object is the provision of a supporting frame of simple construction.

In the accompanying drawings I have shown one embodiment of the invention. In this showing:

30 Figure 1 is a perspective view of a pump casing showing the invention applied,

Figure 2 is a horizontal sectional view on line 2-2 of Figure 1,

35 Figure 3 is a similar view on line 3-3 of Figure 1, and,

Figure 4 is a similar view on line 4-4 of Figure 1.

Referring to the drawings, the reference 40 numeral 1 designates a pump casing having a plunger (not shown) operating therein in the usual manner. The plunger is provided with a plunger rod 2 extending through the top of the casing.

A supporting frame is arranged on top of 45 the casing surrounding the plunger rod. As shown the supporting frame comprises a plurality of upright members 3, the lower ends of which are off-set as at 4 and adapted to be secured to the top of the pump casing.

50 The upper ends of the upright members are connected by a frame 5. This frame is adapted to support a pin or transverse rod 6 and the upper end of a spring 7 is secured thereto. The lower end of the spring is received in a ring 8 carried by a clip or bracket 9 surrounding the plunger rod. A pair of

arms 10 are arranged on one pair of the upright members and a link 11 is pivotally mounted in these arms. As shown, the lower end 12 of the link is substantially Y-shaped and the two arms provided are adapted to receive pivot pins passing through the arms 10. An operating lever 13 extends transversely of the frame and is pivoted to the link 11, as at 14. This lever is provided with an intermediate portion 15 formed of two arms curved with respect to each other and adapted to surround the plunger rod and spring (see Figure 2). A plate 16 is secured to these arms and this plate is provided with a curved portion 17 adapted to receive the plunger rod. A similar plate 18 is secured to the plate 16 and is provided with a curved portion 19 adapted to be arranged on the opposite side of the plunger rod to connect the rod to the operating lever.

A link 20 is pivotally connected to the end of the operating lever by a pin 21. As shown, the pin is provided with a wing nut 22 which may be removed when the link is to be disconnected. This link is also connected to a pivoted lever 23 pivotally mounted on the upper ends of a pair of the upright members 3. A wind mill rod 24 is adapted to be connected to the other end of the lever 23.

The pump is provided with a handle 25 for manual operation, the handle being pivotally mounted on a pin 26 passing through a pair of the upright members. A link 27 is provided with a forked end 28 adapted to surround the handle and connected thereto by means of a pin 29. The other end of the link is pivotally connected to the operating lever 13 by means of a pin 30. This pin is threaded and is provided with a wing nut 31 permitting the handle to be disconnected from the operating lever.

The plunger rod is provided with a guide 32 having a substantially semi-circular recessed face for the reception of the plunger rod. This guide is provided with a pair of arms 33 having offset ends 34 adapted to be secured to a pair of the upright members.

In operation, one of the pins 21 or 30 is adapted to be disconnected. When the pin 30 is disconnected the pump is adapted to be driven by a wind mill in the usual manner, the reciprocation of rod 34 being transmitted to the operating lever 13 through the pivoted lever 23 and link 20. As the operating lever reciprocates the plunger rod is also recipro-

cated. The downward stroke of the plunger rod is an idle stroke as the work to be performed takes place on the upward stroke. Ordinarily the load on the upward stroke has 5 a tendency to retard the movement of the plunger rod and the plunger rod has a tendency to race or speed up on the downward stroke when no work is being performed. In the present construction the spring 7 is 10 placed under tension on the downward stroke and tends to restrain the movement of the plunger. On the upward stroke the tension of the spring assists in lifting the water or other fluid. It will thus be seen that a 15 smoother operation is obtained and vibration is reduced.

When the pump is to be operated by hand, the pin 21 is removed and the link 27 connected to the operating lever by pin 30. The pump is then operated in its ordinary 20 manner.

It is to be understood that the form of my invention herewith shown and described is to be taken as a preferred example of the 25 same, and that various changes in the shape, size, and arrangement of parts may be resorted to without departing from the spirit of the invention or the scope of the subjoined claims.

30 Having thus described my invention, I claim:

1. Pump operating mechanism comprising a supporting frame, said frame consisting of a plurality of upright members adapted to be arranged on the top of a pump casing and surrounding the plunger rod, supporting arms carried by said upright members, a link pivotally mounted in said arms, an operating rod pivotally connected to said link and 35 extending transversely of said frame, means for connecting a plunger rod to said operating lever, a lever pivotally mounted on said frame above said operating rod, one end of said lever being adapted to be connected to 40 a wind mill rod, a link connecting said lever to said operating rod, a handle pivotally mounted on said supporting frame, and 45

means for detachably connecting said handle to said operating rod.

2. Pump operating mechanism comprising 50 a supporting frame, said frame consisting of a plurality of upright members adapted to be arranged on the top of the pump casing and surrounding the plunger rod, supporting arms carried by said upright members, a link pivotally mounted in said arms, an operating lever pivotally connected to said link and extending transversely of the frame, means for connecting a plunger rod to said operating lever, a lever pivotally mounted on 60 said frame above said operating rod and substantially parallel thereto, one end of said lever being adapted to be connected to a wind-mill rod, and a link connected between the free end of said lever and said operating 65 lever.

3. Pump operating mechanism comprising a supporting frame, said frame consisting of a plurality of upright members adapted to be arranged on the top of a pump casing and 70 surrounding the plunger rod, supporting arms carried by said upright members, a link pivotally mounted in said arms, an operating lever pivotally connected at one end to said link and extending transversely of said 75 frame, means for connecting a plunger rod to said operating lever, a lever pivotally mounted on said frame above said operating lever and substantially parallel thereto, one end of said lever being adapted to be connected to a wind-mill rod, a link connecting the free ends of said lever and said operating 80 lever, a handle pivotally mounted on said supporting frame substantially parallel to said operating lever and a link connected between said handle and said operating 85 lever.

In testimony whereof I affix my signature in presence of two witnesses.

GEORGE W. HILL.
